PAUL M. RAINY, OF GLEN RIDGE, NEW JERSEY, ASSIGNOR, BY MESNE ASSIGNMENTS,
TO WESTERN ELECTRIC COMPANY, INCORPORATED, A CORPORATION OF NEW YORK.

TELEGRAPH SYSTEM.

1,174,281.

Specification of Letters Patent.

Patented Mar. 7, 1916.

Application filed December 7, 1914. Serial No. 875,842.

To all whom it may concern:

Be it known that I, PAUL M. RAINY, a citizen of the United States, residing at Glen Ridge, in the county of Essex and 5 State of New Jersey, have invented certain new and useful Improvements in Telegraph Systems, of which the following is a full, clear, concise, and exact description.

This invention relates to telegraph systems of the type wherein a plurality of lines terminate at a central office, and its principal objects are to provide an automatic distribution of incoming calls to idle operators, and to prevent operators from interfering with a busy line.

For the accomplishment of these objects the invention contemplates an automatic operator selector associated with each line, together with means for notifying operators 20 that a given line is busy. An overflow signal is likewise provided whereby notification is given that all the operators on a selector have been found in a busy condition.

25 The above and other objects of the invention will be fully set forth in the following description and claims, and will be more readily understood by reference to the accompanying drawing in which the system is shown diagrammatically.

The telegraph line L, extending from a central office C, may accommodate one or more branch stations 5, each equipped with the usual key 6, sounder 7 and condenser 8. 35 In busy districts there may be a large number of such lines terminating at the central office. Each line is associated at the central office with selecting mechanism whereby, when one of the keys 6 of any station on a line is depressed, such line is automatically connected to the first idle operator's position at the central office.

The selecting mechanism comprises among other apparatus to be presently described, 45 a selector switch 10. This selector switch has an arm 11 carrying a pair of wipers 12 and 13. These wipers are insulated from each other and the arm 11 and are adapted to be carried thereby over a plurality of 50 contacts 14 arranged in pairs. Each pair of contacts 14 is connected to an operator's position set 20, 21, etc., the number of such

positions being determined by traffic conditions. Each set comprises switches 22, keys 23, sounder 24, condenser 25, resistance 26, 55 battery 27 and a signal 28. It will be readily understood that as the arm 11 moves in the direction of the arrow, the wipers 12 and 13 will be successively connected to different operators' positions. Each operator's position set may be, and preferably is, connected through in multiple as shown, to a number of selector switches similar to 10, so that each operator may answer calls originating over a number of telegraph 65 lines.

There are many well known ways of causing the rotary movement of arm 11, but the mechanism preferred consists of a ratchet wheel and a pair of ratchets (not 70 shown) controlled by an electro-magnetic device composed of a stepping magnet 30 and a holding magnet 31. These magnets are intermittently energized when the proper circuit connections are established 75 by interruptions of current caused by a constantly acting interrupter 32. The stepping magnet 30 follows all of these current changes and, upon each energization, causes its ratchet to advance the arm 11 one step 80 in the direction of the arrow. The holding magnet 31 is more sluggish in its releasing action, and when once energized, will not release its ratchet during the intervals of no current produced by interrupter 32. In 85 this way the arm 11 is not allowed to be retracted by its spring (not shown) during short no current intervals, but is released and allowed to return to normal on a longer no current interval. This type of selector 90 switch is well known, one specific form being disclosed in a patent to J. L. McQuarrie, No. 826,350, issued July 17, 1906.

The initiation of the action of selector switch 10 is controlled by a starter relay 35. 95 Starter relay 35 is provided with two armatures 36 and 37, both joined to a grounded battery 38. Line L normally passes by way of a movable contact 40 of a quick acting line extending and interrupter cut-off relay 100 41, through the winding of starter relay 35 to battery 38. When, therefore, the key 6 of any branch station on line L is closed, a circuit is completed for starter relay 35,

which thereupon pulls up its armatures 36 and 37. Armature 36, upon being attracted, grounds battery 38, through magnets 30 and 31, a movable contact 42 of relay 41 and 5 interrupter 32 thereby starting the step-by-step rotation of arm 11.

In order to arrest arm 11 in the proper position for a connection to an idle operator, means are provided whereby the flow of interrupted current through magnets 30 and 31 is stopped when the moving wipers 12 and 13 engage the pair of contacts 14 associated with the first idle operators' position. A lead from wiper 12 is connected to armature 45 of relay 41, while wiper 13 is grounded through the left hand winding 46 of a slow acting relay 47, left-hand winding 48 of relay 41, and right-hand windings 49 and 50 of relays 47 and 41, 10 respectively. For a purpose, to be hereinafter described, the sum of the resistances of windings 46 and 48 is made less than the sum of the resistances of windings 49 and 50. Slow acting relay 47 is provided with 15 two armatures 55 and 56. Armature 55 is connected to battery 38 and armature 56 is grounded and adapted to play between a back contact 57 and a front contact 58. Back contact 57 is joined to a contact spring 20 60 and an armature 61 of relay 41, while front contact 58 is connected to relays 41 and 47 between their right and left-hand windings. Contact 60 is normally held 25 away from engagement with a companion contact spring 62 by an insulating lug on arm 11, but makes engagement therewith upon the first step of the selector switch. In order to break the circuit, including 30 interrupter 32, and provide a steady ground for magnets 30 and 31 during the time of a connection, relay 41 is provided with a grounded armature 63, which when actuated, separates contact 42 from the lead to interrupter 32.

Any or all of the operators provided 35 with sets 20, 21, etc., or other operators, which may be known as sending operators because their positions are not connected to selector switches, may be provided with connecting sets 70, 71, etc. Each of these sets 40 consists of a connecting plug 75, key 76, sounder 78, resistance 79, condenser 80, signal 81 and grounded battery 82. In order that operators provided with sets such as 70 and 71 may communicate with the branch 45 stations on line L, there is placed before each such operator a jack 83, all of the jacks associated with the same line L being connected in multiple and to the wipers 12 and 13 of the selector switch associated with that 50 line. To prevent operators from plugging in on lines already in use, busy signals 85 are provided with each jack 83, all those signals which are associated with a given line L being connected in series with ground

at one end and the front contacts or armatures 37 and 55 at the other end.

When the traffic to certain operators is heavy, it may be found that a line L, desiring a connection, will find all of the operators associated with its selector switch busy, 70 and it is highly desirable that some means be provided to notify the central office attendants that such a selector switch is overflowing so that some of the operators associated therewith may be relieved of a part 75 of their load. This result is accomplished by connecting the last contact of the selector switch 10 through a suitable resistance 90, an overflow of relay 91 and an interrupter 92, to a grounded battery 93. Energization 80 of relay 91 causes the flashing of an overflow signal 94 and, since the insulating segments of interrupter 92 are wide, as shown, the current from battery 93 through contact 14, wiper 13 and relays 41 and 47, is interrupted 85 long enough to effect the complete deenergization of these relays, causing the selector switch to return to its normal position. By making connections as shown at 95, one overflow signal may accommodate several 90 selector switches.

The operation of the system is as follows; When any station on line L desires to make a call, key 6 is depressed closing a circuit for battery 38 through starter relay 35. Starter 95 relay 35 thereupon pulls up its armatures 36 and 37; armature 36 closing a circuit for battery 38, through magnets 31 and 30, contact 42 and interrupter 32. The arm 11 of the selector switch thereupon begins to rotate in the direction of the arrow. The attraction of armature 37 completes a circuit for battery 38 through all of the busy signals 85, thereby notifying operators equipped with sending sets 70, 71, etc., that 100 line L is busy, so that during the display of busy signals 85, one of these operators will not plug into the corresponding jack 83 to connect her set with this line. When the wipers 12 and 13 engage the pair of contacts 14, associated with the first idle operator's position, a circuit is completed from battery 27, switch 22, signal 28, wiper 13 and windings 46, 48, 49 and 50 of relays 110 47 and 41. Signal 28 becomes active, notifying the operator that a telegraphic conversation is desired and relays 41 and 47 attract their armatures. The pulling up of armature 45 connects line L to the idle operator's set, through the wiper 12. The attraction of armature 63 breaks the circuit for interrupter 32 through the magnets 30 and 31, giving these magnets a steady 115 ground, which stops the movement of arm 11 and holds the arm of the selector switch in this position until the call is completed. The pulling up of armature 61 provides a new ground for starter relay 35 through 120 125

contacts 60 and 62, which as previously pointed out, became engaged upon the first step of the selector switch, and, since relay 47 is slower acting than relay 41, the attraction of armature 56 does not break one ground connection for relay 35 until this new ground is provided through armature 61. The attraction of armature 56 short circuits the two higher resistance windings 49 and 50 of relays 47 and 41, providing a lower resistance ground connection on the contact 14 associated with the operator's set, so that if the selector switch of any other line upon which a call is initiated steps upon 15 a contact also connected to this operator's set, insufficient current will flow through the relays thereof which correspond to relays 47 and 41 to cause their energization to stop the movement of the selector switch. 20 This arrangement insures that the selector switches will not step upon the contacts to an operator's set which is already busy, but will pick out the first idle operator. Line L is now connected through to the first idle 25 operator's set, such operator being notified of this fact, by the lighting of signal 28. Messages may be exchanged by the manipulation of keys 6 and 23 in the usual manner, and busy signals are displayed for all of the 30 corresponding jacks 83 associated with line L.

When a call is completed, the operator depresses her release switch 22, whereupon the circuit through the windings 46 and 48 of 35 relays 47 and 41 is opened, causing these relays to release their armatures. The release of armature 45 opens the circuit between line L and the operator. The retraction of armature 61 opens the holding circuit previously 40 traced for starter relay 35, while the return of armature 63 opens the steady ground connection for magnets 30 and 31, and again connects these magnets to the interrupter 32. The interrupter 32, however, cannot cause 45 the operation of magnets 30 and 31 because the deenergization of starter relay 35 has opened the circuit at armature 36. The deenergization of magnets 30 and 31 allows arm 11 to return to its normal position, 50 which condition should be obtained before the armatures of relay 47 are completely retracted. When the armatures of relays 47 are retracted, the apparatus is again in a normal position.

55 In case all of the operators associated with switch 10 are found in a busy condition, upon the initiation of a call upon line L, the arm 11 makes a complete circuit of all of the contacts 14, at last arriving upon the 60 contact connected to the overflow relay 91. This relay will thereupon attract its armature to cause the flashing of overflow signal 94 and, the nonconducting segments of interrupter 92 being made sufficiently long to

effect the complete deenergization of magnets 30 and 31, in precisely the same manner as for a disconnection caused by the central office operator as previously described, whereupon, the selector switch will return to its normal position.

When one of the operators provided with a set 70, 71, etc., desires to be connected with a line L, the plug 75 is inserted in the corresponding jack 83, whereupon a circuit is completed from battery 82, through signal 71 81, plug 75, jack 83 and windings 46, 48, 49 and 50 to ground. Relays 41 and 47 pull up their armatures, as previously described, connecting the operator's set directly through to line L by means of armature 45 80 and contact 40, and operating all of the busy signals 85 before other operators through armature 55. When the telegraphic conversation is completed, the operator withdraws plug 75 from the jack 83, whereupon all of 85 the apparatus returns to normal.

The invention claimed is:

1. In a telegraph system, the combination of a telegraph line extending to a central office, busy signals and sending sets associated therewith at the central office, selecting mechanism for said line adapted to automatically connect said line to one of a plurality of operators' positions, a pair of electro-responsive devices, circuit connections whereby said devices may be brought into action through said line or a said set, and means controlled by said devices to affect said busy signals. 90 95

2. In a telegraph system, the combination 100 of a plurality of telegraph lines terminating at a central office; busy signals and sending sets associated therewith at a plurality of operators' positions at the central office; selecting mechanism for each of said lines 105 adapted to automatically connect said line to one of a plurality of operators' positions and comprising a selector switch having a plurality of contacts, and an electromechanical actuator therefor; multiple circuit connections extending between the contacts of different said switches whereby a plurality of said lines may be extended to a single operator's position; a pair of electroresponsive devices associated with each said mechanism; circuit connections therefor whereby said devices may be brought into action through one of said lines or said sets; and means controlled by said devices to affect 110 said busy signals and the selector switch of 115 any other line having contacts multiplied to the contacts of the switch of the busy line. 120

3. In a telegraph system the combination of a telegraph line extending to a central office, a selector switch automatically operative upon the initiation of a call to connect said line to the first idle operator's position, calling jacks and busy signals associated 125

with said line at a plurality of operators' positions, said busy signals being operated when a call is initiated, and an overload signal operated by said selector switch when all the operators' positions associated therewith are in a busy condition.

In witness whereof, I hereunto subscribe.

my name this 5th day of December, A. D.
1914.

PAUL M. RAINES.
